UNITED STATES PATENT OFFICE.

CHRISTIAN G. FILZER, OF ERIE, PENNSYLVANIA.

HYDROCARBON-TORCH.

1,204,967.

Specification of Letters Patent. Patented Nov. 14, 1916.

Application filed September 20, 1915. Serial No. 51,635.

To all whom it may concern:

Be it known that I, CHRISTIAN G. FILZER, a citizen of the United States, residing at Erie, in the county of Erie and State 5 of Pennsylvania, have invented certain new and useful Improvements in Hydrocarbon-Torches; and I do hereby declare the following to be a full, clear, and exact description of the invention, such as will enable others skilled in the art to which it 10 appertains to make and use the same, reference being had to the accompanying drawings, and to the letters of reference marked thereon, forming part of this specification.

15 My invention relates to hydro-carbon torches, and has for its object the construction of a torch which is adapted to generate combustive gas from kerosene oil; and in which, by slight adjustment, alcohol or gaso-

20 lene may be used.

The features of my invention will be pointed out hereinafter, and are illustrated in the accompanying drawings, in which:

Figure 1, is a side elevation of a hydro-carbon torch apparatus, embodying my invention. Fig. 2, is a plan view of the same, showing a portion thereof in horizontal section. Fig. 3, is a vertical section of a portion of the same on the line y, in Fig. 1. 25 Fig. 4, is an enlarged side elevation of the burner-generator portion of my invention, showing the shell thereof opened. Fig. 5, is a front end view of the same, with a portion thereof in section on the line z, in Figs. 30 4 and 6. Fig. 6, is a plan view of the heating cup and its associate parts, removed from the generator. Fig. 7, is a rear end view of the generator shell illustrating the latch for maintaining it either closed or 35 open as shown by broken lines.

In these drawings A, indicates an air-tight container to hold oil, gasolene or alcohol, or other fluid, and is provided with an air-pump A' of ordinary construction. Se- 45 cured in the container is a hollow stem B, on the top of which is a hollow valve casing B', in which a needle valve B², of ordinary construction operates, which is provided with a stem and hand wheel B³. The stem 50 B, is provided with a tubular extension B'', (see Fig. 3) which extends nearly to the bottom of the container A, as shown by broken lines in Fig. 1. The stem B, is pro- 55 vided with an offset valve casing b, in which a spring-pressed ball check valve b', operates upon a valve seat (see Fig. 3) to pre-

vent backward flow of fluid in the stem B. This valve casing b, communicates with the passage in the hollow stem B, by means of lateral openings b², and b³, and within the 60 hollow stem B, between the lateral openings b², and b³, a screw-plug b⁴, is secured, so that fluid flowing upwardly in the hollow-stem B, must flow through the offset valve-casing b, before it enters the valve- 65 casing B'. Secured in the out-flow end of the needle-valve casing B', is a tubular elbow member C, which has integrally secured to its opposite end a parallel tubular member or cylinder C', the interior of which 70 communicates with the interior of said elbow member C. Fitting against one end of the cylinder C', is another tubular elbow member C'', which is retained in place by means of a screw-rod C³, which extends 75 through the cylinder member C', and engages the elbow member C'', said screw-rod C³, being provided with an enlarged portion c, adapted to fit the opening in the cylinder member C', and is also provided 80 with a handle C⁴, which fits against the outer end of the cylinder member C', so that when the screw-rod C³, is operated, the elbow member C'', may be tightened or loosened as may be desired for the purpose 85 of changing the angle of the elbow member C'', with relation to the needle-valve casing B'. Secured in the elbow member C'', is a tubular member D. In the opposite end of the tubular member D, is secured one end 90 E, of a generator tube, the intermediate portion of which has formed therein a series of helical coils e, the opposite end E', of said generator tube being secured in a return-bend tubular member F, which is se- 95 cured upon and supported by the tubular member D. The return-bend tubular member is provided with a jet opening F', out of which gas generated in the coils e, may flow. Inclosing the coils e, of the tube 100 E—E', is a longitudinally divided shell G—G', the movable part G', being hinged upon the stationary part G, by means of hinges g. The interior surface of the shell G—G', is provided with helical ribs, which 105 enter between the coils e, of the tube E—E', and act to prevent said coils from becoming over-heated during the operation of the torch. I also provide a latch g', (see Fig. 7) which is pivoted upon the part G', of 110 the shell, and engages an upturned lip g², on the movable part G', to prevent the mov-

able part G' , from being opened, or when it is desired to maintain the movable part G' , in the position thereof, shown by broken lines in Figs. 3 and 7, the latch g' , will engage the opposite side of said lip, as shown by broken lines in Fig. 7, and hold said part G' , partially opened. The shell $G-G'$, is provided with a stud-post g^2 , which is secured in an arm F^2 , on the side 10 of the return-bend tubular member F , by means of which the shell $G-G'$, is supported.

Within the shell $G-G'$, is a tube H , the rear end of which is provided with a flange h , which is adapted to close the rear end of the shell $G-G'$, the generator tube $E-E'$, and the stud-post g^2 , passing through openings in said flange h . The flange h , is provided with a boss h' , around the stud-post g^2 , 20 in which the set-screw h^2 , is placed, which is adapted to engage said stud-post, so that the position of said flange and the tube H , with relation to the coils e , can be adjusted as desired, to regulate the heat. Suspended under 25 the shell $G-G'$, is a heating apparatus, by means of which the initial generation of gas in the coils e , may be effected by heat from said heating apparatus, which preferably consists of a combustion frame J , one end 30 of which is secured to the front end of the part G , of the shell by means of a screw j , (see Fig. 5) and the opposite end is supported under the tube D , by means of a pivot pin j' . Under the combustion frame 35 J , and in spaced relation thereto, is a cup frame K , adapted to contain a layer of waste k , in the bottom thereof, as shown in Fig. 5, which may be saturated with oil, or other 40 combustion fluid. I preferably provide an air passage or slot k' , in the cup K , to insure good combustion. This cup K , is pivoted upon the pivot pin j' , so that it can be 45 swung thereon to the position thereof shown by broken lines in Fig. 2, for the purpose of saturating the layer of waste k , with combustion fluid. Upon the pivot pin j' , is pivoted an extinguishing plate L , which is 50 adapted to enter the space between the combustion frame J , and the cup frame K , for the purpose of extinguishing the fire in the cup K , when desired.

To maintain the cup-frame K , in position under the combustion frame J , I provide an overlapping ear J' , on the frame J , which 55 overlaps the cup K , and is provided with a hook j^2 , which enters an opening in the side of the cup K , and then the extinguishing plate L , prevents the raising of the front end 60 of the cup K , so that the same cannot slip off of the hook j^2 . I also provide a latch L' , which is pivoted on the frame J , and is adapted to overlap the edge of the extinguisher L , so that the same will remain in place between the frame J and cup K .

65 I also provide a convenient means to apply

fluid fuel to the layer of waste in the cup K , which consists of a valve M , secured in the container A , which is provided with a tube M' , which extends therefrom nearly to the bottom of the container A . The valve M , is 70 provided with a hand-wheel m , for operating the same, and with a delivery tube M^2 , of sufficient length to extend over the cup K , when the same is in the position shown by broken lines in Fig. 2.

In operation, preferably kerosene oil is placed in the container A , and a sufficient amount of air is pumped into the container to force oil therefrom upwardly through the tube B'' , and check-valve casing b , to the 75 needle-valve B^2 . The latch L' , is then lifted and the extinguisher plate L , is swung out from between the cup K , and frame J , (as shown in Figs. 2 and 6): the front end of the cup K , is then lifted off of the hook j^2 , 80 and is swung laterally past the plate L , until it is underneath the delivery tube M^2 , of the valve M . This valve is then opened and a sufficient quantity of oil allowed to flow therefrom, to saturate the layer of waste k , 85 when the valve M , is closed, and the cup K , returned to its position under the frame J , and in engagement with the hook j^2 .

The latch g' , on the post G' , of the generator shell is then lifted out of engagement 90 with the lip g^2 , on the part G , of said shell, and the part G' , of said shell partially opened and the latch g' , allowed to engage the front side of the lip g^2 , thereby to maintain the part G' , of the generator shell in a 95 partially opened position, as shown in Figs. 3, 5 and 7. The oil soaked waste in the cup K , is then ignited, and the passage of the flame therefrom, through the frame J , insures the perfect combustion, so that the 100 generator will not become coated with soot, but on the contrary, a clean, hot flame will flow from the upper edge of the frame J , into the partially opened generator shell $G-G'$, which will heat the coils e . The 105 needle-valve B^2 , is then opened and oil allowed to flow into the tube $E-E'$, which in passing through the coils e , is transformed into gas, which flows from the jet opening F' , and into the tube H , when it will become 110 mixed with a sufficient quantity of air, and ignite, forming a flame, which projects forwardly through the coils e , and tends to keep said coils hot, so that the generation of gas 115 therein is continuous as long as oil is allowed to flow through the needle-valve B^2 . The latch g' , is now lifted and the part G' , of the shell, allowed to close, and the latch operated to retain the shell closed. The extinguisher plate is then closed in between the frame J , 120 and cup K , and locked. The handle C^2 , is then operated, and the angle of the generator adjusted as may be desired. (See Fig. 1.)

The tube H , may be drawn backward, as 125

shown in broken lines in Fig. 4, for the purpose of increasing the heat within the shell G—G', when first starting the torch; but I have found that said tube H, can soon be returned to the position thereof shown by solid lines in Fig. 4. The flange h, is provided with a series of holes h³, (see Figs. 3 and 5) to supply air into the shell G—G', around the tube H, in order to prevent excessive heating of the generator.

Having thus shown and described my invention so as to enable others to construct and operate the same, what I claim as new, and desire to secure by Letters-Patent, is:—

- 15 1. In an apparatus of the class described, a generator shell, a helically coiled tube in the front end thereof having the ends thereof extending rearwardly out of the rear end of said shell, means to supply fluid to one end of said tube, a gas-jet concentric with the rear end of said shell, a tubular connection between the opposite end of said helically coiled tube and said gas-jet, and a gas and air mixing tube within the rear end of said shell between the ends of said helically coiled tube, said mixing tube extending from the rear end of said shell to a point adjacent to the rear coil of said helically coiled tube, substantially as set forth.
- 20 2. In an apparatus of the class described, a helically coiled tube, a shell inclosing said tube, helical ribs on the interior surface of said shell which enter the spaces between the several coils of said tube, a gas and air mixing tube concentrically arranged in the rear portion of said shell, a jet tube supported adjacent to the rear end of said gas and air mixing tube, a tubular connection between one end of said helically coiled tube and said jet tube, and means to supply fluid to the other end of said coiled tube, substantially as and for the purpose set forth.
- 25 3. In an apparatus of the class described, a helically coiled tube, a longitudinally divided cylindrical shell inclosing said tube, latch mechanism adapted to retain said shell closed or open as may be desired, a longitudinally adjustable gas and air mixing tube concentrically arranged between the rear portion of said shell and said helically coiled tube, a jet tube arranged to discharge gas

into the rear end of said mixing tube, a tubular connection between said jet tube and one end of said helically coiled tube, means to supply fluid to the other end of said helically coiled tube, and means adjacent to said helically coiled tube to initially heat the same, substantially as set forth.

4. In an apparatus of the class described, a helically coiled tube, a stationary semi-cylindrical shell inclosing one side of said tube, a movable semi-cylindrical shell hinged upon the upper edge of said stationary shell, a latch lever pivoted on one of said shells, a projection on the other of said shells, said lever having means adapted to engage either side of said projection, substantially as and for the purpose set forth.

5. In an apparatus of the class described, an initial heating apparatus consisting substantially of a frame having longitudinal walls therein forming an air slot therebetween, and a cup-member having an air-slot in the bottom thereof and adapted to contain combustion material therein, pivotally arranged under said frame, substantially as and for the purpose set forth.

6. In an apparatus of the class described, a torch nozzle, a combustion frame secured thereunder, a cup-frame adapted to contain combustion material pivotally secured in spaced relation under said combustion frame, and an extinguishing plate mounted on the pivot of said cup and adapted to enter the space between said frame and cup, substantially as and for the purpose set forth.

7. In an apparatus of the class described, a container, a vertical tube connected therewith, a parallel tube integrally secured on the side thereof having a valve-seat therein, a spring-pressed ball on said valve-seat, lateral openings from the first named tube into the parallel tube above and below said valve-seat, a closure-plug in said first named tube, between said lateral openings, a valve-casing communicating with said vertical tube, a valve therein, a torch nozzle, and a tubular connection between said valve casing and said nozzle, substantially as set forth.

In testimony whereof I affix my signature.

CHRISTIAN G. FILZER.
